UNITED STATES PATENT OFFICE.

DAVID L. GRIFFITHS, OF OLYPHANT, PENNSYLVANIA.

CURRYCOMB.

1,083,087.

Specification of Letters Patent.

Patented Dec. 30, 1913.

Application filed January 24, 1912. Serial No. 673,282.

To all whom it may concern:

Be it known that I, DAVID L. GRIFFITHS, a citizen of the United States, residing at Olyphant, in the county of Lackawanna and State of Pennsylvania, have invented a new and useful Currycomb, of which the following is a specification.

The present invention relates to improvements in curry-combs, the primary object 10 of the invention being the provision of a pneumatic or suction device adapted to have connected detachably thereto a curry-comb which forms a sealing means for the vacuum chamber of the device and is provided with 15 a plurality of apertures therethrough leading into the vacuum chamber, whereby the hair and dust and dirt loosened from the skin of the animal will be drawn through the said apertures into the vacuum chamber of the device and finally to any desired 20 receptacle.

A further object of the present invention is the provision of a novel form of casing which has removably mounted therein a 25 curry-comb provided with apertures therethrough to provide inlet nozzles for the air into the vacuum casing, the latter forming in reality the back of the comb and being provided with means for readily applying 30 the device as is the usual custom in combing.

With the foregoing and other objects in view which will appear as the description proceeds, the invention resides in the combination and arrangement of parts and in the details of construction hereinafter described and claimed, it being understood that changes in the precise embodiment of 35 invention herein disclosed can be made 40 within the scope of what is claimed without departing from the spirit of the invention.

In the drawings—Figure 1 is a view illustrating the use of the comb, the same being 45 shown operably connected to an electrically operated suction creating device. Fig. 2 is a transverse section through the comb, said section being taken on the line X—X Fig. 4. Fig. 3 is a section on line Y—Y Fig. 2. Fig. 4 is a bottom plan view of the curry 50 comb.

Referring to the drawings, 1 designates an electrically operated suction creating engine, the same, however, being indicative of 55 any form of suction mechanism, either operated by power or by hand if so desired.

Leading from the suction engine is the usual flexible hose 2 which is removably attached to the coupling end 3 of the inlet nozzle of the casing 4, which forms the back or gripping portion of the curry-comb as will presently appear.

In order properly to manipulate the device a hand strap 5 is connected to the casing 4 while a strap 6 is placed upon the forearm of the operator and is formed with a loop 6' fastened upon the suction hose 2, the connection at 6' and the hand strap 5 keeping any undue strain from the connection of the hose to the coupling end of the nozzle 3. 60 70 80

By this means a free action is permitted in the movement of the comb over the hide of the animal.

As clearly shown in Fig. 2, the casing 4, is provided with a domed top 7 and a downwardly projecting rim 8, which has mounted upon the inner side thereof and also connected to the under side of the dome 7, the short rim 9 provided with an end plate 10 which thus provides an abutting means for 85 removable curry-comb plate 16 so that when the plate is placed in position for use a vacuum or suction chamber 11 is provided between the under side of the dome 7 of the casing 4 and the opposed face of the 90 95 curry-comb plate 16.

The inner end 15 of the suction nozzle 3 is flared and terminates at a point slightly beyond the center of the dome 7, thus causing the air to be drawn through the orifices 90 18, respectively, of the curry-comb plate 16, and finally through the enlarged mouth 15 into the reduced portion 3 and thence through the suction hose 2 to the desired place of deposit.

The curry-comb consists of the plate 16, which is provided with a peripheral rim 17 whose lower edge is provided with the usual teeth or serrations, the body of the plate 16 being further provided with air inlets 100 apertures 18 which provide a means of communication between the chamber formed between the rim 17 and the hide of the animal and the vacuum chamber 11 of the casing 4. In order to provide further means for combing, two U-shaped currying strips or plates 19 and 19' are secured to and carried by the plate 16 within the outer flange or rim 17, and are provided with their serrations or teeth upon the lower edges, while 110 disposed longitudinally of the plate, 16 as shown in Fig. 4, is a curry-comb plate or

strip 21 which is provided upon its outer edge with the usual teeth or serrations. Cut from the central portion of the plate 21 adjacent the plate 16 is a slot 22 which permits the free egress or passage of the air, so that the same may enter any of the various apertures 18. Formed in the body of the respective curry-comb plates 19 and 19' are similar notches or recesses 23.

- 10 From the foregoing description, taken in connection with the drawings it is evident that a curry-comb constructed according to the present invention provides a means whereby the dust and dirt which usually is freed and commingles with the atmosphere, is drawn through the body of the curry-comb into the vacuum chamber with the hair, and is deposited or collected in any well known manner through the medium of 15 any form of suction creating device. By this means the dust and dirt loosened from the hide of the animal is removed in a sanitary and thorough manner.

What is claimed is:

- 25 A curry comb comprising a hollow body having a rim forming an open-ended receptacle, a wall paralleling the rim within the

same and terminating in a shouldered portion, a nozzle of flattened frusto-conical shape disposed within the body, a plate 30 movably sealing the open end of the body and having a plurality of apertures therethrough, a rim, having a serrated edge, carried by the plate and forming an open-ended air-confining chamber below the plate, a 35 strip secured centrally and longitudinally upon the under side of the plate and provided with a plurality of teeth upon its edge and two curved strips provided with teeth upon their lower edges and secured to 40 the plate and paralleling the adjacent end of the rim thereof, the central strip dividing the chamber longitudinally and having its ends terminating in spaced relation to the curved strips to provide circulating passages 45 at the center thereof.

In testimony that I claim the foregoing as my own, I have hereto affixed my signature in the presence of two witnesses.

DAVID L. GRIFFITHS.
